HEBON B. LAYMAN, OF NEW YORK, N. Y.

INTERNAL-COMBUSTION ENGINE.

1,144,422.

Specification of Letters Patent. Patented June 29, 1915.

Application filed June 29, 1914. Serial No. 847,870.

To all whom it may concern:

Be it known that I, HEBRON B. LAYMAN, a citizen of the United States, and residing at New York, in the county of New York and State of New York, have invented certain new and useful Improvements in Internal-Combustion Engines, of which the following is a specification, such as will enable those skilled in the art to which it appertains to make and use the same.

This invention relates to explosion or internal combustion engines and particularly to engines of this class of the sleeve valve type, and the object thereof is to improve the construction of and method of assembling the parts of an engine of this class so as to facilitate finishing and assembling of said parts and render the same more practical and economical without decreasing in any way the efficiency of such engines, and with this and other objects in view the invention consists in the construction, combination and arrangement of parts hereinafter described and claimed.

The invention is fully disclosed in the following specification, of which the accompanying drawing forms a part, in which the separate parts of my improvement are designated by suitable reference characters in each of the views, and in which:—

Figure 1 is a central vertical section of the top portion of the cylinder of an explosion engine made according to my invention together with the explosion head of the cylinder and the inlet and exhaust manifolds. Fig. 2 a view similar to Fig. 1 but showing a modification; and, Fig. 3 a view similar to Figs. 1 and 2 but showing another modification.

In the drawing forming part of this specification, I have shown at *a* the top portion of the cylinder of an explosion engine containing the usual piston *b*, and at *c* I have shown the explosion head of the cylinder which is formed separately and insertible from the bottom of said cylinder. The cylinder *a* is provided with an extension *a*² which forms an inclosing casing or jacket for the explosion head and, in the construction shown, the said extension *a*² is reduced in size, and the top portion of the explosion head and said casing or jacket are both of less transverse dimensions than the cylinder, thus producing a contracted and inwardly inclined shoulder *a*³ at the top of the cylinder, and the bottom of the explosion head *c* is pro-

vided with an annular enlargement *c*² which abuts against the shoulder *a*³ when the head is inserted from the bottom of the cylinder. I have also shown at *d* and *e* the inlet and exhaust manifolds of the engine, and said manifolds are provided with inlet and exhaust ports or passages *d*² and *e*² controlled by a sleeve valve *f* movable in a sleeve valve chamber *g* formed between the top cylindrical portion *c*³ of the explosion head *c* and the extension *a*² of the cylinder. The cylinder *a* is also inclosed by the usual casing or jacket *a*⁴, which unites with the extension *a*² of the cylinder just below the inlet and exhaust manifolds *d* and *e*, as shown at *a*⁵, and in the construction shown the parts *a*, *a*², *a*⁴ and *d* and *e* are all formed integrally but this is not absolutely necessary. The extension *a*² of the cylinder, or the casing or jacket formed by said extension and the explosion head *c* are provided with a detachable cap *h*, and while I have shown but one cylinder it will be understood that the engine, in practice, is made up of a number of such cylinders and the cap *h* applies to all of them.

The explosion head *c* of the cylinder is provided with an explosion chamber *c*⁴, the lower end portion of which communicates with the cylinder and is funnel-shaped in form as shown at *c*⁵, and the top portion of which is provided with a transverse partition *c*⁶ having a threaded bore or passage *c*⁷ in which the sparking plug is secured, said sparking plug being not shown. The explosion head *c* is also provided with an annular water chamber or passage *c*⁸ which incloses the explosion chamber and the lower end portion of which is enlarged as shown at *c*⁹ to correspond with the annular enlargements *c*² at the bottom of the explosion head and, in the construction shown, the bottom and top walls of the annular enlargement *c*⁹ of the water chamber or passage *c*⁸ are reinforced or braced at *c*¹⁰. The detachable cap *h* is also put in communication with the water chamber or passage *c*⁸ by means of ports or passages *h*² and the inclosing casing or jacket *a*⁴ of the cylinder forms a water chamber or passage *i* which incloses the cylinder and the bottom part of the explosion head and is placed in communication with the annular enlargement *c*⁹ of the water chamber or passage *c*⁸ by ports or passages *i*², and in the use of the engine the water from the radiator enters the bottom portion

of the chamber or passage i in the usual manner and passes upwardly around the cylinder and into the bottom portion of the explosion head and up through the chamber i or passage c^8 and into the detachable cap h from which it passes back to the radiator in the usual manner. With this construction the top portion of the cylinder and the extension a^2 thereof which forms the inclosing 10 jacket or casing of the explosion head may be machined or finished separately as may also the explosion head, and in this operation the valve chamber g is also finished as will be readily understood and the valve is inserted before the cap h is applied, and by means of this method of forming, finishing and assembling said parts, the expense of forming and finishing the valve chamber is largely reduced, and the assembling of the 20 parts facilitated, as will be readily understood. The explosion chamber c^4 of the explosion head is provided with an upwardly directed extension c^{11} on which is screwed a nut j which bears on the cap h and aids in drawing the explosion head into position and securing it therein.

In the construction shown in Fig. 1, the vertical or longitudinal dimensions of the explosion chamber c^4 are much greater than 30 the transverse dimensions, and the valve chamber, or the casing thereof, is water-jacketed only on the inner side thereof, this result being obtained by reason of the fact that the water chamber or passage c^8 is formed in the explosion head of the engine, but in Fig. 2 I have shown a modification in which the explosion chamber c^4 is shortened and enlarged transversely, and in this form of construction the water casing or jacket a^4 35 which incloses the cylinder a is extended upwardly and incloses the inlet and exhaust manifolds d and e and the valve chamber g , or the annular casing forming the valve chamber is water-jacketed on the outer side 40 only instead of on the inner side as shown in Fig. 1, the upward extension a^6 of the casing or jacket a^4 which incloses the inlet and exhaust manifolds forming a supplemental water chamber or passage i^3 which 45 is in communication with the chamber or passage i , as shown at i^4 , and the water chamber or passage i^3 is in communication with the cap h as shown at i^5 , and the cap h is also enlarged transversely, and with these 50 exceptions the construction shown in Fig. 2 is the same as that shown in Fig. 1.

In Fig. 3, I have shown another modification in which the valve chamber g , or the casing thereof, is water-jacketed both on the 60 inner and outer sides thereof, the explosion head c^4 being provided inwardly of said valve chamber, or the casing thereof, with the water chamber or passage c^8 as shown in Fig. 1, and also with the water chamber or passage i^3 as shown in Fig. 2. In this form

of construction, the water chamber or passage i^3 is placed in communication with the bottom of the explosion head or the water chamber or passage c^8 therein, as shown at i^2 and the water flows up through 70 the chamber or passage i into the chamber or passage i^3 and into the bottom of the chamber or passage c^8 , and from the chamber or passage c^8 and the chamber or passage i , the water flows into the cap h in 75 the same manner as in Figs. 1 and 2, and with this form of construction, the valve f , or the casing thereof, is water-jacketed on both sides and there is a complete flow of 80 water in a continuous direction on both sides of said valve or valve casing, as indicated by the arrows x , and arrows x also indicate the flow of the water in Figs. 1 and 2.

In all the forms of construction shown 85 the explosion head as well as the valve and valve chamber are of less transverse dimensions than the cylinder, but my invention is not limited to this construction, all that is necessary, in this respect being, that the 90 dimensions of said parts be such as to permit the insertion of the explosion head from the bottom of the cylinder and the proper fitting of said explosion head in the top end 95 of the cylinder, or the extension thereof.

Having fully described my invention, what I claim as new and desire to secure by Letters Patent, is:

1. In an explosion engine, a cylinder provided with an extension above the working portion thereof, an explosion head which is inserted into said extension from the bottom of the cylinder, the extension of the cylinder and said explosion head forming an annular valve chamber above the working portion of the cylinder, and a sleeve valve placed in said chamber and above the working portion of the cylinder and independent thereof.

100

2. In an explosion engine, a cylinder provided with an extension above the working portion thereof, an explosion head which is inserted into said extension from the bottom of the cylinder, the extension of the cylinder and said explosion head forming an annular valve chamber above the working portion of the cylinder, and a sleeve valve placed in said chamber and above the working portion of the cylinder and independent thereof, said cylinder and said explosion head being also provided with a removable cap and said

105

cylinder being provided with a water jacket forming a main water chamber or passage, and said explosion head and said cap being also provided with water chambers or passages which are in communication and also in communication with the main water chamber or passage.

110

3. In an explosion engine, a cylinder provided with an extension above the working

115

120

125

130

portion thereof, an explosion head which is inserted into said extension from the bottom of the cylinder, the extension of the cylinder and said explosion head forming an annular

5 valve chamber above the working portion of the cylinder, and a sleeve valve placed in said chamber and above the working portion of the cylinder and independent thereof, said cylinder and said explosion head 10 being also provided with a removable cap and said cylinder with a water jacket forming a main water passage and said explosion head being provided within the valve chamber with a water circulating passage 15 in communication therewith, and said cap being also provided with a water chamber or passage in communication with that within the explosion head.

4. In an explosion engine, a cylinder provided with a reduced extension at the bottom of which is an annular shoulder, an explosion head containing an explosion chamber and insertible from the bottom of the cylinder and between which and said 25 extension is a valve chamber, said explosion

head being provided at its lower end with an annular enlargement which abuts against said shoulder.

5. In an explosion engine, a cylinder provided with a reduced extension at the bottom of which is an annular shoulder, an explosion head containing an explosion chamber and insertible from the bottom of the cylinder and between which and said extension is a valve chamber, said explosion 30 head being provided at its lower end with an annular enlargement which abuts against said shoulder and the explosion chamber in said head being inclosed by a water chamber or passage having an inlet at the bottom 35 and an outlet at the top.

In testimony that I claim the foregoing as my invention I have signed my name in presence of the subscribing witnesses this 25th day of June 1914.

HEBRON B. LAYMAN.
